UNITED STATES PATENT OFFICE.

JOSEPH KOEHLER, OF NEW YORK, N. Y.

DESIGN FOR AN ENVELOP.

SPECIFICATION forming part of Design No. 27,854, dated November 16, 1897.

Application filed August 18, 1897. Serial No. 648,726. Term of patent 14 years.

To all whom it may concern:

Be it known that I, JOSEPH KOEHLER, a citizen of the United States, residing in the city, county, and State of New York, have invented and produced a new and original Design for Envelops, of which the following is a specification, reference being had to the accompanying drawings, forming part thereof.

The nature of my design is shown in the accompanying drawings, in which—

Figure 1 is a rear elevation of an envelop showing my new design; and Fig. 2 is a transverse section on the line 2 2, Fig. 1.

Similar letters of reference indicate corresponding parts.

As shown in the drawings, the leading and main feature of my design consists of an ornamental border extending along three unconnected sides of the closing-flap of the envelop, said border representing conventionalized lacework.

The envelop C is shown in the drawings as of oblong form, but this form is no part of the invention, while the flap B is shown of corresponding form. The border A is shown as 25 extending along the three unconnected sides of the closing-flap B, the dimensions of the flap and the border being such that the edges of the flap do not quite extend up to the edges of the envelop.

Having described my invention, what I claim as new, and desire to secure by Letters Patent, is—

The design for an envelop, substantially as shown and described.

In testimony that I claim the foregoing as my invention I have signed my name in presence of two subscribing witnesses.

JOSEPH KOEHLER.

Witnesses:
